INVENTOR

John. Israel.

UNITED STATES PATENT OFFICE.

JOHN ISRAEL, OF DAYTON, OHIO.

BURGLAR-ALARM.

SPECIFICATION forming part of Letters Patent No. 224,017, dated February 3, 1880.

Application filed June 6, 1879.

To all whom it may concern:

Be it known that I, JOHN ISRAEL, of Dayton, in the county of Montgomery and State of Ohio, have invented certain new and useful Improvements in Burglar-Alarms, of which the following is a specification.

My invention relates to that class of burglar-alarms which are applied to doors and windows to guard them, as exemplified in Letters 10 Patent of the United States No. 193,002, granted to me July 10, 1877.

In the accompanying drawings, Figure 1 is a front elevation, and Fig. 2 is a side elevation, of my apparatus.

15 The percussion-tube A, its plunger, and the match-holder a are similar in construction to those shown in my patent above mentioned, and are mounted upon the lamp-cylinder, as in said patent. The lamp-cylinder B is mounted 20 upon a foot or bracket, b, which bends or projects outward, and is secured upon a carrying-plate, C. This cylinder has a filling-hole, b', which is tightly closed by a screw-plug, b''. The wick-tube D is made conical in shape, 25 with the smaller end upward, and has a tightly-fitting conical cover, d, secured to a chain, the other end of which is fastened to the match-holder a.

30 A suitable reflector, E, is carried by an arm, e, pivoted to the carrying-plate back of the lamp-cylinder, and can be swung around its pivot, so as to be out of the way when not in use.

An alarm-bell, F, is secured upon the carrying-plate just below the lamp-cylinder, and is sounded by a simple clock-work and bell-clapper of ordinary construction. The bell F is screwed upon the winding-post, so that the clock-work can be wound up by simply turning 40 the bell.

A tripping rock-shaft, K, is secured upon the carrying-plate in eyes k. One end, k', of this shaft is turned up and looped over the hammer or plunger of the percussion-tube, 45 and the other, k'', is turned up so as to engage with the trigger j of the alarm-bell mechanism.

The operation of my improved burglar-alarm, when organized as above described, is 50 as follows: The apparatus is to be so secured upon the jamb of a door or window that the hammer of the percussion-tube, when set, will be tripped by any movement of the same.

The hammer being set, the rock-shaft turned outward so that its end k'' will engage with 55 the trigger of the alarm-bell, and the bell being properly wound, should the hammer be tripped from any cause it will plunge forward, explode the cap, ignite the match and lamp, and trip the alarm mechanism of the bell by 60 means of the rock-shaft.

In addition to the tripping rock-shaft above mentioned, I provide a tripping-shaft, L, which is turned up at each end, one of which ends 65 serves as a handle, and the other, l, engages with the trigger of the alarm-bell mechanism, so that the alarm-bell may be sounded and stopped simply by rocking this shaft back and forth.

The end l, which engages with the alarm-bell trigger, is turned up so as to move in the same path with the end k'' of the rock-shaft, so that should it be desired to use the bell as a call-bell when the entire alarm is set, it will only be necessary to rock the shaft L, the end 75 l of which will move the end k'' of the rock-shaft out of engagement with the trigger without exploding the cap. By this means I am enabled to utilize the apparatus during 80 the hours of the day as an ordinary call-bell.

The manner of applying this apparatus to doors and windows is well understood, and need not, therefore, be described.

By dispensing with the lamp and alarm-bell mechanism and simply using the percussion-cap as an alarm, and providing a suitable trip to be used in connection therewith, I produce 85 a pocket-alarm for travelers which can be temporarily secured upon a door or window.

Having thus described my invention, what 90 I claim as new, and desire to secure by Letters Patent, is—

1. The combination of the plunger, the rock-shaft, and the alarm-bell mechanism, substantially as described.

2. The combination of the rock-shaft, the alarm-bell mechanism, and the tripping-shaft L, whereby the alarm-bell can be utilized as a call-bell, substantially as described.

In testimony whereof I have hereunto 100 subscribed my name.

JOHN ISRAEL.
